GAS HAMMER

Spencer B. Maurer and Howard P. Ebert, Cleveland, Ohio, assignors to Chicago Pneumatic Tool Company, New York, N. Y., a corporation of New Jersey

Original application August 15, 1946, Serial No. 690,654. Divided and this application July 8, 1949, Serial No. 103,662

9 Claims. (Cl. 125—33)

1

This invention relates generally to percussive tools in which the motive power is derived from an integrally formed internal combustion engine, and more particularly to improvements to a tool of this type in which the driving piston is returned through its compression stroke by the momentum of a fly-wheel and crankshaft operatively connected to the driving piston. A tool of the class to which this invention relates is illustrative by a gas hammer for which a Patent No. 2,333,419, was issued to Clifford E. Fitch on November 2, 1943.

In the illustrative embodiment of the present invention, a tie tamper is driven by a gasoline powered single cylinder, two cycle, air-cooled engine designed to impart rapid downward blows to the tamping bar which is mounted vertically in the lower end of the tool. The engine is mounted directly atop a cast aluminum housing which is the main body of the tool and to which are secured a gasoline supply tank, a carburetor, air cooling apparatus, hammer piston barrel, and manipulative handles. The location of these handles in line with and just above the center of gravity of the tool assembly insures a proper balance for easy handling of the device. The tool is operated by one man who grasps the two handles near the top where most of the weight is concentrated and directs the tool by placing the spade of the tamping bar in position and allowing the tool to drive the stone ballast under the ties as desired. The operator then lifts the tool to another spot to repeat the operation, the tool continuing to operate during the transfer movement. Thus the tool operates continuously without any loss of time.

An object of the invention is to provide a novel arrangement of the tamping bar in relation to the driving elements which will be highly effective in operation.

A further object is to improve the structural arrangement of the striking piston, the piston cage, and the piston barrel so that these members will operate more efficiently in combination with each other and as a means of transmitting power from the main crankshaft to the tamping bar.

Other objects of the invention are to provide a tamping bar arrangement in a percussive tool having the above objects in mind, which is simple in construction, has a minimum number of parts, easy to assemble and take apart, compact and efficient in operation.

Other objects and structural details of the invention will be apparent from the description when read in conjunction with the accompanying drawings, wherein:

Fig. 1 is a view, in perspective, of the tool of the present invention, shown adapted for the tamping operations, with the starter handle in the lowered position;

2

Fig. 2 is a longitudinal sectional view taken generally along the line 2—2 of Fig. 1, the lower part of the tool being shown in elevation;

Fig. 3 is an enlarged longitudinal sectional view taken generally along line 3—3 of Fig. 1, showing the striking hammer and cage in lowered or foremost position in contact with the working implement;

Fig. 4 is a cross-section as indicated by the arrows 4—4 in Fig. 3;

Fig. 5 is a strobotac chart of the hammer position shown in relation to the vacuum, open port, and pressure regions of the striking cage at progressive angular positions of the crank.

As shown in Fig. 1, the tool of the invention is a portable, unitary structure which may be manipulated by one or two men by means of properly and conveniently disposed handles 13 and 14. For purposes of description, the tool may be considered as divided into a plurality of cooperating sections or parts including an upper portion 15, a downwardly extending barrel 16, and a barrel extension or nose 17. Extension or nose 17 supports a working implement 18 which, in the present instance, is a tamping bar. Referring also to Fig. 3, the inner end of the bar 18 projects into the barrel 16 in position to receive blows of percussion from a hammer piston 19. The piston 19 forms part of a free piston type hammer assembly and moves within a cylindrical cage 20 slidably mounted within the barrel 16. The cage 20 is reciprocated by power transmission means connected to the driving piston 21 of the internal combustion engine, Fig. 2. The transmission means, hereinafter more fully described, comprises an engine crankshaft 22 driven by the piston 21, a main crankshaft 23 actuated by the engine crankshaft 22 through pinion and gear means, and a connecting rod 24 between the main crankshaft 23 and the cage 20. The reciprocating action of cage 20 imparts repetitive hammering action to the hammer piston 19 as hereinafter described.

The bar 18, maintained in operative position within the barrel 16 and barrel nose 17, is pressed into engagement with the work by the operator during operation of the tool and is driven outwardly by repetitive blows of percussion delivered upon its inner end by the hammer piston 19. The adjacent ends of the barrel 16 and the barrel nose 17 are provided with flanges 25 and 26 respectively which are secured together by bolt means 27. As best shown in Fig. 3, a locating sleeve 28 to maintain the tamping bar 18 in alignment with the barrel and nose is disposed within the outer end of the barrel nose 17 and is provided at its inner end with a flange 29 which seats upon an inwardly projecting shoulder 30 of the nose 17. Sleeve 28 is made in two pieces having complementary recesses forming a hexagonal opening for the bar 18. The

sleeve 28 is retained against axial movement by a preloaded compression spring 31 which is arranged within the nose in compression between the sleeve and a lower two-piece snubber ring 32. The latter ring abuts a retainer ring 33 which is seated in fixed position between the upper end of the nose 17 and shoulder 34 adjacent the flange 25 on the lower end of the barrel 16. Abutting the inner end of the retainer ring 33 is an upper snubber ring 35 which is maintained in such abutting position by a preloaded compression spring 36 extending between the ring 35 and an internal annular flange 37 upon the barrel 16. The resistance of the spring 36 is such as to maintain ring 35 in abutting relationship with retainer ring 33 and thereby to maintain the tamping bar in predetermined position under the weight of the tool as positioned for normal operations. The lower snubber ring 32 is formed with an internal annular seat 38 and the upper snubber ring 35 is provided with an internal annular seat 39, said seats being arranged in opposition to form with the intervening retainer ring 33 a chamber 41 within which a collar or flange 42 on the tamping bar 18 reciprocates. The tamping bar is driven downwardly or outwardly by the blow of the hammer piston 19, the collar 42 sometimes striking the seat 38 of the lower snubber ring 32 which yields with the preloaded compression spring 31. If the tamper bar 18 is held off the ground with the machine in operation the spring 31 reacts to force the bar upwardly after each blow, driving it against the seat 39 of the upper snubber ring 35 where its force is absorbed by said ring as yieldingly reinforced by the preloaded compression spring 36. The upper snubber ring 35 is formed with an upwardly projecting cylindrical flange 43 which, in conjunction with the sleeve 16, maintains the tamping bar in axial alignment with the hammer piston 18.

The tamping bar is driven in its working operations by blows percussively imparted by the striking or hammer piston 19 which is slidably mounted in cage 20, Fig. 3. Cylindrical cage 20, which is made from seamless steel tubing, is provided at its ends with annular enlargements or shoulders 44 and 45 which slidably engage the inner wall of barrel 16. The mid-portion of the cage 20 is of reduced external diameter to provide an annular space 46 between the cage and the barrel, and said portion of reduced diameter is formed with a series of circumferentially spaced ports or openings 47 to cooperate with a groove 48 in the piston 19 as hereinafter more fully described. The shoulders 44 and 45 are formed with circumferentially-arranged longitudinal recesses 49 which serve to connect the annular space 46 respectively with chamber 52 of the main crankshaft and barrel chamber 53, Figs. 3 and 4. Continuous communication is thus established between the top and bottom of the cage to minimize pressure fluctuations. The chambers 52 and 53 may be vented by exhaust ports 52' and 53' or alternatively may be enclosed from the atmosphere and maintained at any suitable pressure. In any event, the pressure fluctuations in chambers 52 and 53 are slight, due to the equalizing effect of recesses 49 which transfer air from one chamber to the other and thereby inhibit compression in either chamber as a result of the movements of cage 20 and piston 19. Cage 20 is connected to the connecting rod 24 by means of a pivot pin 55 which is passed through aligned holes in the upper end of the

cage and in the lower terminal of the connecting rod 24. An aluminum head 56 fits snugly within the upper end of cage 20 to form an airtight closure for a chamber or air pocket 57 which lies above hammer piston 19. The head is transversely bored to receive the wrist pin 55 and is provided at its upper end with a square recess to receive the lower end of the connecting rod. The cage head 56 has a downwardly protruding portion 58 which fills up a considerable part of the air pocket 57. Reciprocating movement is imparted to the cage 20 by the connecting rod 24, and is transmitted through the air pocket 57 to the striking piston 19, as will shortly appear.

The striking or hammer piston 19 has a sliding fit with the inner wall of the cage 20 and is formed with a lower face 58 which functions as a hammer surface to strike the upper face of the tamping bar 18. The piston 19 is formed with a cup shaped recess 59 in its upper portion and with circumferential groove 48 approximately midway its length. Groove 48 is connected to recess 59 by radial ports 60, so that upon the registration of ports 47 with groove 48 the interior of the cage 20 is connected to atmosphere through recess 59, ports 60, groove 48, ports 47, space 46, recesses 49, chambers 52 and 53, and exhaust ports 52' and 53'. Recess 59 is shaped to loosely receive the protruding portion of cage head 56, and forms a continuation of the pocket 57. Upon downward movement of the cage 20, air is compressed within such pocket 57 forcing the piston 19 downwardly to strike the tamping bar 18. At this point the circumferential ports 47 in the cage are brought into registration with the groove 48 in the piston, and the compressed air in the pocket is set free. The cage 20 thereupon moves upwardly during the ports 47 out of registration with the groove 48 and a partial vacuum or area of low pressure is created in the cage pocket 57. This will cause the piston to follow the cage upwardly until the ports and groove are again in registration. The momentum of the hammer piston 19 carries it upwardly for a short time after the cage has started downwardly, thereby forming a compressed air cushion which prevents the hammer piston from striking the cage. As the cage continues downwardly, the compressed air forces the piston downwardly to begin a new cycle.

Reference is made to the chart, shown as Fig. 5, for a graphic explanation of the movement of the cage 20 and hammer piston 19 in relation to the angle of the main crankshaft 23. In operation, the cage 20, whose position relative to the barrel 16 is depicted by four solid lines, reciprocates through a two inch stroke, being driven by the crankshaft at approximately 1400 revolutions (or reciprocations) per minute. The piston 19, represented by broken lines, operates inside the cage and its movement is affected by the cage only through the air pressure in the chamber or pocket 57 above the piston 19. When the machine is standing up resting on the bar 18 with the cage 20 at the bottom of its stroke and the piston 19 down on the bar, the port holes 47 in the cage register with the groove 48 in the piston. When the cage rises, the ports in the piston are closed and a partial vacuum is created in the closed chamber 57 between the piston and cage head. This creates a net upward force on the piston causing it to rise after the cage. This accelerating force continues to increase until the piston attains a higher velocity than that of the cage which occurs under

normal operation somewhere around 280° but under starting conditions may occur later. Then the accelerating force begins to decrease although the upward velocity of the piston continues to increase until the piston and cage ports again line up and atmospheric pressure is restored to the air chamber 57 and 59. This occurs at about 330° under normal operation, and at top dead center the piston ports again close off as the piston rides into the pressure pocket or upper portion of the cage. The upward velocity of the piston is then reduced as its energy is absorbed by the air being compressed in the pressure pocket 57. At about 60° past T. D. C. the piston has lost its upward motion and starts downward. Since the cage is moving downward at a now increasing rate (due to the crank angle) the piston and cage continue to move relative to each other building up a still higher air pressure in the air pocket 57 as some of the kinetic energy of the rotating parts is converted and stored in the compressed air. At about 90° past T. D. C. the piston has attained the same velocity as the cage (maximum cage velocity occurring at this point), and peak air pressure has been attained. From this point to 155° the piston 19 is accelerated above cage speed as the energy stored in the air is returned to the piston in the form of increased downward velocity. At this point, 155° past T. D. C., the ports are again opening and the piston has attained its maximum downward velocity. The piston then strikes the bar 18 at about 170° crank angle just as the vacuum pocket 57 is again about to close.

The exact point at which the bar 18 is struck depends upon the relative location of the bar to the rest of the machine. If no downward force is applied to the machine by the operator, the machine will tend to rise until the bar collar 42 is down close to the snubber ring 32 as illustrated diagrammatically in Fig. 5. The piston having struck the bar transfers a large portion of its energy to the bar and rebounds upward with a low velocity as shown on the chart. The upward velocity of the cage exceeds that of the piston at about 200° past T. D. C. and the piston rides into the vacuum pocket 57 and starts a new cycle. Any loss of air from the pressure pocket through leakage around the piston 19 is made up when the cage and piston ports line up again allowing atmospheric air to enter. This tends to maintain constant conditions from one cycle to the next and insures uniform operation.

Compared with a prior commercial structure, which is shown in Fitch Patent 2,333,419, the primary advantages of the present type cage and piston arise from the removal of the bottom pressure pocket and the change in character of the top pocket. The volume of the top pocket has been increased so that more air is available to be compressed. This means that a lower peak pressure will be attained in absorbing the upward energy of the piston and returning it in a downward direction. The length of the piston stroke while in the pressure pocket will as a result also be increased so that the lower average pressure will impart the same energy to the piston. This reduction in peak pressure means reduced forces on all rotating parts and less vibration of the whole machine. The protruding portion 56 of the aluminum cage head 55 is designed to fit down inside the hollow portion of the piston 19 when the piston is near the top of the pressure pocket. This is necessary so that the final volume of the air chamber at peak pressure

will be small enough to prevent the piston from actually touching the cage head.

The removal of the bottom pressure pocket of the old design eliminated the possibility of the piston riding into this pocket at full striking velocity if snubber failure should allow the bar to drop below normal level. This happened quite frequently on the old machine when the rubber snubbers failed causing breakage of magneto parts, crankcase housings, crankshafts and other fairly rugged parts of the machine. In the new machine a vacuum pocket on top of the piston has replaced the lower pressure pocket and as a result if snubber failure should occur the piston will ride right through the vacuum pocket and thus it drops out of engagement with the cage ports and ceases to operate until the bar has been restored to its proper position. This happens when the piston port groove 49 drops below the bottom of the cage. It is impossible for the piston to come completely out of the cage.

The peak force that can be exerted on the piston or cage by the vacuum pocket 57 is not large, since little is required to raise the piston on the up stroke of the cage during normal operation. When the piston does drop out of the cage vacuum pocket it ceases to strike the bar 18 and the motor speeds up thus advising the operator that something is wrong and at the same time preventing further operation which might harm other parts of the machine.

Still comparing the present invention with its predecessor, both the cage and the piston are simpler in design and much cheaper to manufacture. Several difficult precision grinding operations have been eliminated and the total lathe time considerably reduced. The great reduction in weight of the reciprocating parts has reduced the inertia forces which contribute to vibration of the entire machine. The elimination of the scotch yoke and substitution of the light weight cage and connecting rod was an important improvement along this line.

The machine is further protected from shock loading by the two preloaded snubber springs 36 and 31 which limit the upward and downward motion of the bar by absorbing the energy from the bar in either direction at relatively low peak forces. Approximately $\frac{1}{8}$ " of bar shake is provided before the bar collar 42 contacts either spring. In normal tamping operations, with the operator applying a slight downward pressure on the machine, the bar collar is about $\frac{1}{8}$ " away from the ring 32 on the lower snubber spring 31, and since the bar travel per blow is much less than this, the bar collar does not contact either ring 32 or ring 35. However, when the machine is being lifted, the lower snubber spring 31 absorbs the full energy of downward motion of the bar and returns the bar upwards at a reduced velocity due to energy having been lost in friction chiefly between the bar and the two hexagonal bushings 43 and 28 which guide it. The function of the upper snubber spring 36 is to absorb the energy of the upward motion of the bar 18 and return it in a downward direction. The bar may oscillate back and forth several times before the energy is dissipated and the next blow is struck.

The upper portion 15 of the tool contains the internal combustion engine and controls therefore, including the starting mechanism and flywheel magneto. In the illustrative embodiment the engine is of the two-cycle type. The principal supporting element for the engine is a frame piece or crank case 61, to which is bolted a cover

61a, the frame piece and cover being made of aluminum, and cooperating to form an air-tight crankcase chamber 62 through which the connecting rod 63 passes. The driving piston 21 reciprocates within a cylinder 64 in the cylinder head 65 secured to the frame in conventional manner. It will be seen that the piston 21 divides the interior of the cylinder 64 in such a way as to separate the upper chamber 66 from the lower chamber 62 which chambers may be respectively identified as the "combustion chamber" and the "pre-compression chamber." A mixture of gasoline and air is introduced into the combustion chamber 66 through a port 67 in the cylinder 64 while burned gases resulting from the explosion within the cylinder will escape through an exhaust port 68. The port 67 communicates with a transfer passage 69 formed in the cylinder head. The flow of gasoline and air into the precompression chamber 62 is controlled by a carburetor, not shown.

Transfer passage 69 communicates also with the precompression chamber 62 by a port 70 in the piston, whenever port 70 registers with a complementary cylinder port. The port 67 is controlled by the piston 21 and is open only in the lowermost operative position of the piston, as in Fig. 7. In the operation of the engine an explosive charge, previously introduced into the combustion chamber 66 is ignited by a spark plug 70a mounted in the cylinder head 65 and extending into chamber 66. The piston 21 is thereby driven downward through its power stroke, and near the end of its downward movement uncovers exhaust port 68. Shortly after the opening of such port, the piston 21 uncovers port 67 and a pre-compressed mixture of gasoline and air flows into the combustion chamber 66. The mixture is directed upwards by deflecting surface 74 on the head of the piston 21 and forces the burned gases downward and out of the exhaust port 68. Near the start of the upward or return stroke of the piston the port 67 and exhaust port 68 are closed. As the piston 21 continues its upward movement the precompression chamber 62 expands in size and draws a fresh mixture of air and gas from the carburetor. The fresh gases are prevented from entering the combustion chamber 66 at this time. While a new charge is thus drawn into the precompression chamber 62, the one previously admitted to the chamber 66 is compressed and, as the piston reaches its uppermost position, is ignited and explodes. The downward movement of the piston resulting from the explosion again reduces the size of the precompression chamber 62 and the gases within the chamber are first compressed and later transferred through the supply passages 69 to the upper chamber 66. The engine thus completes a cycle of operation in two strokes or one reciprocation of the piston; each descent of the piston being a power stroke occasioned by an explosion in the combustion chamber.

The left hand end of the engine crankshaft extends into the crankcase chamber 62 and has keyed thereto, a crank arm 79. Arm 79 has an outwardly projecting stud 81 extending into the connecting rod 63 and is also formed with a counterweight 83.

For effecting return motion of the piston 21 and thereby of the piston hammer assembly, a fly-wheel 84 is mounted upon the outer end of the engine crankshaft. The kinetic energy stored in the fly-wheel 84 on the power stroke of the piston 21, in conjunction with the counterweight 83, is

10 sufficient to continue the rotation of the crankshaft 22 and to transmit through the crank arm 79 and connecting rod 63 force for the return stroke of the piston 21. The connection between the rod 63 and the crankshaft 22 is such that they are constrained to move in unison, and operation of either element effects a simultaneous operation of the other. Their relationship as driven and driving elements is mutual and reversible.

15 The ignition system of the tool includes a fly-wheel magneto mechanism 92 for generating an electric current which is supplied through a cable 85 to the spark plug 70a and is adapted to supply interrupted current under the control of suitable timing or circuit breaking mechanism. The fly-wheel magnet mechanism is mounted upon the right hand end of the crankshaft 22, and retained against longitudinal movement along the shaft by a suitable nut 90 and washer 91.

20 The engine crankshaft 22 drives the main crankshaft 23 by means of pinion 93 on the engine crankshaft and the gear wheel 94 which is integral with the main crankshaft. Main crankshaft 23 is rotatably mounted in the frame 61 by needle bearings 96 and ball thrust bearings 97, and is provided at its forward portion with splines which form a pinion 98 to cooperate with the toothed clutch ring 99 on shaft 107. The inner face of gear wheel 94 is provided with a stud 101 which projects into the terminal portion 103 of the cage connecting rod 24. Connecting rod 24 is connected at its lower end to the cage 20 by pin 55. It thus may be seen that the reciprocal motion of the engine or driving piston 21 is transmitted through the connecting rod 63 and the crankshaft arm 79 to impart rotary motion to the engine crankshaft 22 and that in operation the engine crankshaft 22 drives the main crankshaft 23. Crankshaft 23, through the cage connecting rod 24, acts as a reciprocating driver for the cage 20.

25 The starter shaft 107 is mounted in the frame 61, its end portions being supported by needle bearings 118 and 119 which are carried respectively by the frame 61 and the starter cover 121.

30 In the illustrative embodiment the total gear ratio from the starter shaft 107 to the engine crankshaft 22 is 11.4 to 1. Thus a quarter turn of the starter shaft will turn the engine over approximately three times. A rapid downward thrust of the starter handle 13 through its normal ten inch stroke (approximately one-quarter turn of starter shaft) will produce more than three full revolutions of the engine at a fairly high speed.

35 The gear ratio between the engine crankshaft 22 and the main crankshaft 23 is about 2.85 to 1. The advantages of using a high speed motor with gear reduction are more power per cubic inch of motor, more cooling air with a smaller fan, better magneto operation (hotter spark) and smoother operation due to larger number of smaller motor impulses and accentuated fly-wheel effect of the rather heavy magneto rotor.

40 When the tool is not in operation the starter handle 13 is maintained in locked position against one side of the tool by the latching mechanism 134. When the tool is in operation, the starter handle is clear of the latching mechanism, as in Fig. 1. Latching mechanism 134 comprises a stud 135 screwed into the frame 61, a latch 136 which is pivotally mounted on the outer end of the stud and is provided with a handle 137, a helical spring 45 138 mounted upon the stud to urge the latch out-

ward, a nut 139 preventing outward movement of the latch, and a cotter pin 140 to secure the nut on the stud 135. The spring is formed with an extending terminal 141 which is in pressing engagement with the frame 61 at 142. When the operator shuts off the motor and desires to lay the tool aside, as is frequently required under working conditions on the railroad tracks, he slams the starter handle upwardly and inwardly. The cross bar 146, in the area indicated at 147, then strikes the outer end 148 of the latch handle 137 camming it upwardly and clockwise against the resistance of the helical torsion spring 138. As the upward and clockwise motion of the cross bar continues, the bar in the area indicated at 149 strikes the projection 151 of the latch causing a further camming action upwardly until the cross bar finally clears the latch. The handle is thus quickly locked into a position which is inoperative for starting purposes but operative in the sense of enabling the manipulation of the machine during tamping operations. It is not necessary for the operator to transfer his grip from the starting handle after starting the machine since this handle is also used for manipulating the unit. To unlock the latch, it is merely necessary for the operator by manipulative pressure to lift the latch in a clockwise direction, slightly beyond the horizontal position and move the starter handle 13 outwardly in a clockwise direction to the position shown in Fig. 1. He then by a quick thrust of the starter handle can start the motor.

The air cooling system has been provided for the tool and serves not only to cool the engine but to keep other parts of the tool at a temperature that is comfortable for the operator. The rear face of the fly-wheel 84 is provided with a circumferential row of fan blades 154 which drive a steady current of air as indicated by the arrows upwardly and into the space beneath and within the aluminum hood 156. Air is supplied through the screened passage 155. The hood, which is secured to the frame 61, extends completely over the engine and is formed with a downwardly turned skirt 157 which extends below the exhaust manifold 158. This extension of the hood below the exhaust port forms an important feature of the invention. The exhaust gas is driven from the piston chamber 66 at high speed tending to create a low pressure area in the confined space within the adjacent hood and thereby implements the fans in the circulation of the air cooling supply. To facilitate such circulation the exhaust deflector 158 is shaped with a tapered throat as in the case of a jet pump.

The exhaust deflector 158 may be removed whenever it is desired to scrape carbon from the exhaust port 68. To this end the deflector is attached to the cylinder head 65 by means of screws 160 which are readily accessible through holes 161 in the hood 156.

The illustrative machine will operate for over three hours without refilling the gas tank, and no lubrication, other than oil mixed with the gasoline is required. The entire machine is lubricated by the oil mixed with the gasoline in the ratio of about 16 to 1. A portion of this oil is diverted from the engine crankcase 62 and sprayed into the main crankcase 52 in a fine mist where it thoroughly lubricates all parts and gradually drains down through the machine running out along the bar 18. This continual oil flow has a purging effect as it tends to wash out any dirt that may get into the machine. The starter

parts are also well lubricated by oil seeping into the starter compartment of the housing through the needle bearing 96 which supports the main crankshaft between the two compartments.

The leakage of oil from the engine crankcase through the shielded ball bearing 77 to the main crankcase occurs during each precompression stroke of the engine when the pressure in the engine crankcase exceeds that in the main crankcase 52. Lubrication of the engine parts is not impaired and the quantity of oil lost as smoke through the engine exhaust 158 is reduced.

This application is a division of applicant's parent application Serial No. 690,654, filed August 15, 1946, which issued as Patent No. 2,533,487, on December 12, 1950. Additional divisions of the same parent application are as follows: Serial No. 175,742, filed July 25, 1950, contains claims to a combined engine and tool; Serial No. 176,984, filed August 1, 1950, contains claims to a cooling system for an internal combustion engine; and Serial No. 248,076, filed September 19, 1951, contains claims for an engine starter mechanism.

What is claimed is:

1. In a percussive tool, a housing, a barrel member mounted thereon, a hammer assembly including a floating hammer member adapted to reciprocate within the barrel, a working implement arranged within the barrel and having a collar thereon, said implement being adapted to transmit intermittent blows of the floating hammer member, a retainer ring mounted in the barrel and extending into the interior thereof adjacent the implement collar, an inner snubber ring formed with a shoulder adapted to seat the collar, an outer snubber ring formed with a shoulder adapted for seating the collar and disposed opposite the inner snubber ring shoulder, the retainer ring serving to space the two opposite snubber ring shoulders apart a greater distance than the thickness of the collar, to provide a space wherein the collar may float snub-free, and spring means within the barrel adapted to maintain the snubber rings in contact with the retainer ring when the tool is at rest, the outer snubber ring and associated spring means being adapted to absorb the shock of the collar at a predetermined point upon its outward movement in response to a blow of the floating hammer and the inner snubber ring and associated spring being adapted to absorb the shock of the collar at a predetermined point upon its reaction from the outer spring thereby to intermittently position the working implement at a predetermined point for the reception of intermittent hammer blows.

2. A hammer assembly comprising containing means, a hollow member slidably therein having an intermediate portion in spaced relation to the containing means and formed with connecting means leading from the intermediate space to atmosphere and with separate connecting means from the intermediate space to the interior of the member, a floating hammer slidable within the hollow member and adapted to form with the hollow member an air-tight chamber, said hammer being provided with means including a passageway adapted to connect the chamber to the space between the containing means and the hollow member, the foregoing elements being so arranged that upon movement of the hollow member in one direction a region of low pressure will be formed adapted to cause the floating hammer to trail the hollow member and upon movement of the hollow member in the other direction a

region of high pressure will be formed adapted to cause the floating hammer to move in such other direction, the regions of low and high pressure being brought to atmospheric pressure upon the registering of the connecting means of the container with the connecting of the hammer.

3. In a percussive tool of the class wherein the striking implement is driven by repetitive blows from a reciprocating free piston, in combination, a tubular member; a hollow cylindrical member reciprocable therein and having a central portion in spaced relation thereto, the space so formed having connecting means to the interior of the cylinder and to atmosphere; a floating hammer member within the cylindrical member forming therewith an air-tight chamber and having means therethrough adapted to cooperate with the foregoing connecting means to form an air connection between said space and said chamber, said hammer being adapted to trail the cylindrical member upon the formation of a region of low pressure by the movement of the member in one direction and being adapted to move in the other direction to impart a hammer blow under pressure created by the cylindrical member in moving in the other direction; percussion means disposed within the tubular member and adapted to be actuated by intermittent blows of the hammer means; preloaded compression spring means to maintain the percussion means in predetermined position; and precompression spring means initially spaced from the percussion means and operative to yieldingly limit the movement of the percussion means in response to the blows of the hammer member.

4. In a percussive tool, a hammer assembly comprising a hollow cylinder provided with shoulders at its opposite ends with an internally projecting head and with a mural port between the shoulders; a piston hammer member reciprocable therein formed with a recess opposite the cylinder head and with a peripheral groove connected to the recess by at least one passage, said cylinder and hammer piston being adapted to form an air-tight enclosed chamber therebetween; and a containing member adapted to slidably enclose the cylinder to form a cylindrical space therebetween, said members being so arranged that the cylinder upon movement in one direction will create a region of low pressure in the chamber thereby to cause the hammer piston to trail the cylinder and upon movement in the other direction will create a region of high compression to drive the hammer piston in the opposite direction, the regions of low and high pressure being opened to atmosphere by the registration of the piston passageway with the mural port of the cylinder.

5. In a percussive tool of the class wherein the striking implement is driven by repetitive blows from a reciprocating free hammer piston, in combination, containing means, a tubular member spaced therefrom and having longitudinally recessed shoulders at its opposite ends and at least one port intermediate the shoulders, said shoulders providing slidable means for the tubular member within the containing means and the longitudinal recesses forming access to atmosphere for the space between the containing means and the tubular member, a floating hammer piston slidably mounted within the tubular member and formed with a recess in its upper portion, a groove in its periphery, and at least one passage connecting the groove and the recess, and a head member associated with the tubular member

adapted in conjunction with the hammer piston and tubular member to form a completely enclosed chamber therebetween, said elements being so arranged that the tubular member with associated head upon movement in one direction will compress the air in the chamber to drive the hammer piston in one direction and upon movement in the other direction will create a region of low pressure sufficient to cause the hammer piston to trail the tubular member.

6. In a percussive tool of the class wherein the striking implement is driven by repetitive blows from a reciprocating free hammer piston, in combination, a stationary containing member; a 15 slidable member adapted to reciprocate within the containing member comprising a tubular central portion with at least one mural port, shoulders at the opposite ends of the tubular portion formed with recesses adapted to connect to atmosphere 20 the space between the containing and slidable members, and a head member having a projection extending longitudinally into the tubular portion; and a floating hammer member reciprocable within the slidable member and having a recess 25 adapted to form with the slidable member, including the internally projecting head, a completely enclosed air-tight chamber, said hammer member having a peripheral groove connected to its recess by at least one passageway; and the 30 arrangement of the members being such that the port of the slidable member may be brought into registration with the peripheral groove of the hammer member thereby to connect the enclosed chamber at atmosphere.

35. 7. In a percussive tool, a housing, a motive power device, an impact element actuatable thereby in a predetermined path, a percussion tool positioned with one end in said path to be struck by the impact element, said tool having a shoulder 40 element, a pair of co-axially aligned helical snubbing springs disposed on opposite sides of said shoulder element, and means for spacing the adjacent inner ends of the two springs to provide a minimum free floating space for the tool 45 shoulder.

8. A percussive tool, as in claim 7, including a floating end ring for the inner end of each spring, and a spacer to separate the two floating end rings to provide a free floating space for the tool 50 shoulder.

9. A percussive tool, as in claim 8, in which each floating end ring is provided with a shoulder to be engaged by the tool shoulder in the corresponding direction of movement of the tool.

55 SPENCER B. MAURER.
